UNITED STATES PATENT OFFICE

161,545

TOY BIRD FIGURE

Ivy Laverne Shinn, Dallas, Tex.

Application July 10, 1950, Serial No. 11,033

Term of patent 14 years

(Cl. D34—2)

To all whom it may concern:

Be it known that I, Ivy Laverne Shinn, a citizen of the United States residing at Dallas, county of Dallas, and State of Texas, have invented a new, original, and ornamental Design for a Toy Bird Figure, of which the following is a specification, reference being had to the accompanying drawing, forming a part thereof.

I claim:

The ornamental design for a toy bird figure, as shown.

IVY LAVERNE SHINN.
